UNITED STATES PATENT OFFICE.

KARL SCHNITER, OF FRANKFORT-ON-THE-MAIN, GERMANY, ASSIGNOR TO THE FIRM OF VEREINIGTE KUNSTSEIDEFABRIKEN A. G., OF KELSTERBACH-ON-THE-MAIN, GERMANY.

PROCESS FOR THE PREPARATION OF NITROCELLULOSE.

1,093,012.

Specification of Letters Patent.

Patented Apr. 14, 1914.

Application filed March 18, 1913. Serial No. 755,129.

To all whom it may concern:

Be it known that I, KARL SCHNITER, citizen of Switzerland, residing at Frankfort-on-the-Main, Germany, have invented certain new and useful Improvements in Processes for the Preparation of Nitrocellulose, of which the following is a specification.

Nitro-cellulose is prepared by treating cellulose with nitric acid, or a mixture of nitric and sulfuric acids. It has hitherto not been possible to prevent the charge (*i. e.* the mixture of nitro-cellulose and acid) from occasionally taking fire. In unfavorable cases, more particularly when the nitro-cellulose is already freed from the greater part of the acid, the combustion takes place with explosive rapidity resulting in considerable damage to the apparatus and to the building. It has been attempted to control this difficulty by washing the charge with other acid mixtures but it has not proved possible to overcome the difficulty in this way.

According to the present invention combustion of the charge is entirely prevented by washing the nitro-cellulose immediately after the nitration has been effected, with cooled acid, which treatment prevents combustion without in any other respect acting on the nitrated material. The cooled waste acid from a previous operation is preferably used, and in this manner the material is lowered to a temperature at which spontaneous decomposition is made impossible.

It has heretofore been proposed to influence the nitration itself by fresh and cold acid. However, even under these conditions, combustion of the charge occurs occasionally. According to the present invention however, combustion of the charge is entirely obviated by washing the nitro-cellulose with cooled acid after the nitration has taken place.

In order to carry out the nitration an apparatus is employed which is built on the principle of the continuously circulating dye bath. The apparatus is shown in section in the accompanying drawing.

a is a vessel provided with a removable lid, in which vessel the nitration takes place. An outflow pipe *b* is provided be-

low leading to a pump *c*, from which a pipe *c'* passes to discharge the liquid into the cells *d*, arranged within the vessel *a*, containing the material to be nitrated. The bottoms *e* of these cells are perforated. The apparatus is resistant to acid and does not allow the acid to escape. When the pump *c* is started the acid from the vessel *a* is forced by the pump through the pipe *c'* on to the cotton in the cells, penetrates therethrough and runs back into the vessel *a* through the perforated bottoms *e*, the circulation of acid being continued while the pump is in operation. When the nitration is completed, the pump *c* is shut off and the acid in the cells *d* is allowed to run off. As soon as this is done, the cooled acid from an earlier operation is allowed to drop from a second container *f* over the nitrated material until the latter has been sufficiently cooled. The material is then centrifugalized from the acid and further treated in the usual manner.

What I claim as my invention is:—

1. The herein described method of preparing nitro-cellulose, which consists in completely nitrating cellulose in a single bath of nitrating acid, and thereafter subjecting the nitrated cellulose to a bath of a similar acid at a lower temperature than that of the acid first employed, under such conditions that said nitrated cellulose is cooled and its chemical constitution remains unchanged.

2. The herein described method of preparing nitro-cellulose, which consists in completely nitrating cellulose in a single bath of nitrating acid, and thereafter subjecting the nitrated cellulose to a bath of cooled waste acid from the first bath, under such conditions that said nitrated cellulose is cooled and its chemical constitution remains unchanged.

In testimony whereof I affix my signature in presence of witnesses.

DR. K. SCHNITER.
